COMBINED WAFFLE BAKER AND GRILL

Robert O. Ernest, Oak Park, Ill., assignor to Sunbeam
Corporation, Chicago, Ill., a corporation of Illinois

Application March 30, 1955, Serial No. 35,274

Term of patent 14 years

(Cl. D81—10)

Fig. 1

Fig. 2

Fig. 3

Fig. 4

Fig. 5

Fig. 1 is a perspective view of a combined waffle baker and grill embodying my new design;

Fig. 2 is an enlarged top plan view;

Fig. 3 is a front elevational view;

Fig. 4 is a side elevational view; and

Fig. 5 is a rear elevational view.

The dominant features of my design reside in the full line portion of the drawings.

I claim:

The ornamental design for a combined waffle baker and grill, substantially as shown and described.
